(57) CLAIM

The ornamental design for a chair, as shown and described.

DESCRIPTION

FIG. 1 is a perspective view of a chair.

FIG. 2 is a front elevation view of the chair.

FIG. 3 is a right side elevation view of the chair.

FIG. 4 is a rear elevation view of the chair.

FIG. 5 is a left side elevation view of the chair; and,

FIG. 6 is a top plan view of the chair.

The broken line disclosure is for illustrative purposes only and forms no part of the claimed design. The disclosure associated with brackets is shown to indicate indeterminate length of the chair.
